UNITED STATES PATENT OFFICE.

WILLIAM H. FREUNDT, OF HAMMOND, INDIANA, ASSIGNOR TO BENJAMIN H. VOSS, OF CHICAGO, ILLINOIS.

NOTE-BOOK HOLDER.

1,251,006.

Specification of Letters Patent. Patented Dec. 25, 1917.

Application filed November 21, 1914, Serial No. 873,383. Renewed September 7, 1917. Serial No. 190,273.

To all whom it may concern:

Be it known that I, WILLIAM H. FREUNDT, a citizen of the United States, residing at Hammond, in the county of Lake and State 5 of Indiana, have invented certain new and useful Improvements in Note-Book Holders, of which the following is a specification.

This invention relates to book supports and more particularly to a holder for supporting stenographers' note books and the like, and the primary object of my invention is to provide a note book support of the above character which will be simple in construction, cheap to manufacture, and is 15 collapsible and easily capable of packing in a small space.

Another object of my invention is to provide means for retaining the note book in position on the support, and also to provide 20 means for adjusting the support at a desired angle.

With the above and other objects in view my invention resides preferably in the construction, combination and arrangement of 25 parts as hereinafter set forth in the specification and illustrated in the accompanying drawings, in which:—

Figure 1 is a perspective view of my improved book support;

30 Fig. 2 is a side elevation of the same showing the manner of supporting a note book, the note book being illustrated in dotted lines.

Fig. 3 is a fragmental detail in plan showing the formation of the offset portions in 35 the divergent arm.

Similar reference characters indicate similar parts throughout the various views of the drawings.

40 Referring more particularly to the drawing in which the preferred embodiment of my invention is illustrated, I provide a frame preferably formed of a single strand of wire 1 into substantially rectangular configuration to provide the side portions 2 and 3. The free ends of the single strand of wire 1 are twisted together as shown at 4 and bent into parallelism with the frame 1 to afford a book holder.

50 The side portions 2 and 3 are provided with eyes 7, said eyes being formed at the upper corners of the frame 1. Side portions 2 and 3 are also provided at a point substantially intermediate the ends with eyes 8, said

eyes 8 being formed by looping the strands 55 of wire.

In order to maintain the frame in an inclined position to support a note book, I provide a supporting leg formed of a single strand of wire 9, the said strand of wire 9 60 being bent upon itself intermediate the ends as shown at 10, to provide parallel portions twisted as shown at 11 and slightly offset at 12 to provide a loop, the said offset portion being bent inwardly at 13. The strand of 65 wire 9 is formed to provide divergent arms 14, the outer end of the said divergent arms 14 being provided with eyes 15 for engagement with the eyes 7, so as to hingedly mount the said supporting leg on the frame. The 70 strand 9 is provided with a loop 16 to afford a foot.

In order to retain the supporting leg at a desired angle to the frame I provide a brace member formed of a single strand of wire 75 and bent upon itself to provide divergent arms 17, the said divergent arms having their outer ends provided with eyes 18 for engagement with the eyes 8 of the frame. The strand of wire forming the arms 17 is 80 sinuated to provide offset portions of varying sizes, designated 19 and 20, which are adapted to embrace the arms 14, as shown to advantage in Fig. 1. The constricted portions 21 formed by the sinuation of the 85 strand of wire affords a throat through which the inwardly bent portions 13 of the arms 14 may pass to adjust the latter. This arrangement permits the disengagement of the arms 14 and the brace by moving said 90 arms through the throat. This will allow the frame and the supporting leg to be brought together, and the brace member will at this time be swung upwardly into parallel relation with the frame and the supporting leg 95 so that a minimum space is taken by the device when folded.

In order to adjust the frame to different angles the divergent arms may be inserted between the offset portions 20, these portions 100 being slightly shorter than the portions 19 and of course are nearer the point at which said brace member is hinged, thereby changing the inclination of said frame.

The manner in which a book is supported 105 on my improved device will be readily appreciated by those skilled in the art, a note book indicated by the numeral 23 being

shown in dotted lines in Fig. 2, one portion of said note book being receivable within the back or retaining element 4, and the other portion being receivable within the retaining element 16, the body of the book embracing the frame and supporting leg.

There are but three principal parts to my invention, all three of which parts may be formed, as stated in the specification, of wire or the like which tends to simplify the construction of the device. There are no plates of sheet metal or the like secured to the device, there is no soldering, and the device is readily collapsible for package into a small space.

While I have shown and described my invention as possessing a peculiar form and construction, it is desired that it be understood that I may make such changes in the details thereof as do not depart from the spirit and scope of the invention as claimed.

Having thus described my invention, what I claim and desire to secure by Letters Patent, is:—

25 1. A book support, including a rectangu-

lar frame, a supporting leg pivoted at the upper corners thereof and having divergent arms, and a brace formed of a strand of wire pivoted intermediate the height of said frame and situated on its free extremity to 30 brace said divergent arms, whereby to allow adjustment of the angle of inclination of said frame.

2. A book support, including a frame, a supporting leg formed of a single strand of 35 wire bent and twisted to provide divergent arms pivoted to said frame, a brace member formed of a single strand of wire situated to provide offset portions of varying sizes to embrace said divergent arms, said brace being pivoted to said frame, whereby to maintain the latter at a desired angle of inclination.

In testimony whereof I affix my signature in presence of two witnesses.

WILLIAM H. FREUNDT.
